UNITED STATES PATENT OFFICE.

PATRICK McFADDEN, OF PHILADELPHIA, PENNSYLVANIA.

HARNESS-SADDLE.

SPECIFICATION forming part of Letters Patent No. 284,039, dated August 28, 1883.

Application filed February 12, 1883. (Model.)

To all whom it may concern:

Be it known that I, PATRICK McFADDEN, of Philadelphia, in the county of Philadelphia and State of Pennsylvania, have invented certain new and useful Improvements in Harness-Saddles; and I do hereby declare the following to be a full, clear, and exact description of the invention, such as will enable others skilled in the art to which it pertains to make and use it, reference being had to the accompanying drawings, which form part of this specification, in which—

Figure 1 is a plan view; Fig. 2, a longitudinal vertical section; Figs. 3 and 4, details of my improvement.

My invention has relation to harness-saddles; and it consists in the combination, with the saddle and back-strap, of a bridge of special construction, and a roller for the support and play of the back-strap, as hereinafter described and claimed.

Referring to the accompanying drawings, A represents the saddle, which is of the ordinary construction.

25 a a are the adjustable pads, secured to the saddle by bolts a' a', passing through the ends of the terret-loops b b, and by bolts a² a², passing through lateral plates b² b² of the bridge.

B represents the bridge, consisting of a hollow rectangular box or body having the top B', end flanges, c c, side flanges, c' c', laterally-extending plates b² b², and openings c² c², through the side flanges, c' c', for the passage of the back-strap C, and holes c³ c³ in the end flanges, c c, through which the crupper-loop and the bearing-strap pass. The crupper-loop and bearing-hook may be secured as shown in Fig. 1—that is, they may have a thread cut upon their shanks, upon which 40 nuts d d are screwed; or the latter may be at-

tached to the bridge, as shown in Fig. 4, wherein the shank of the hook passes through a slot, e, in the top of the bridge, and is bent around and secured by a bolt, e', passing through it and the bridge-top. Beneath the 45 bridge, and at the center of the saddle, is journaled a roller, f, in uprights f' f'. The back-strap C rests upon and passes over this roller, and passes through the terret-loops b b, being free to slip back and forth under the bridge. 50

The advantages of the construction shown are briefly as follows: The crupper-loop and bearing-hook being secured solely to the bridge, and the latter being secured to the saddle by bolts which pass into the saddle-pads, there is no danger of injury to the horse's back by protruding bolts, as heretofore. The back-band being attached to the saddle in such manner that it has freedom of movement back and forth, there is less strain on the saddle 60 and less danger of galling the animal's back. The adjustable pads being secured to the saddle by the same bolts that hold the bridge and terret-straps, there is a consequent saving of labor and material. 65

What I claim as my invention is as follows:

The combination, with saddle A, back-strap C, and roller f, of the bridge B, having end flanges, c c, in which are secured the crupper-loop and bearing-hook, and having also the 70 lateral plates b² b² and openings c² c², substantially as described.

In testimony that I claim the foregoing I have hereunto set my hand this 10th day of February, 1883.

PATRICK McFADDEN.
